UNITED STATES PATENT OFFICE.

BERNARD H. CAMDEN, OF PARKERSBURG, WEST VIRGINIA.

MONEY-CHANGING MACHINE.

1,172,108.

Specification of Letters Patent. Patented Feb. 15, 1916.

Application filed February 23, 1915. Serial No. 10,077.

To all whom it may concern:

Be it known that I, BERNARD H. CAMDEN, a citizen of the United States, residing at Parkersburg, Wood county, and State of 5 West Virginia, have invented and discovered certain new and useful Improvements in Money-Changing Machines, of which the following is a specification.

My said invention relates to machines for 10 making change, particularly to machines adapted for automatically selecting coins that will aggregate the change required when the amount of the purchase and the amount of money tendered in payment are 15 known, the machine being also adapted for throwing out any given amount in change up to a fixed maximum, and it consists in various improvements in the construction and arrangement of the parts, whereby such 20 a machine is provided of a comparatively simple and inexpensive construction and one that is not only reliable and accurate in its operation, but not likely to get out of order, all as will be hereinafter more fully described 25 and claimed.

Referring to the accompanying drawings which are made a part hereof and on which similar reference characters indicate similar parts, Figure 1 is a top or plan view of a 30 money changing machine of my improved construction, Fig. 2 a horizontal section, as seen when looking downwardly from the dotted line 2—2 in Fig. 3, Fig. 3 a vertical section, as seen when looking in the direction indicated by the arrow from the dotted line 3—3 in Fig. 2, Fig. 4 a transverse section on the dotted line 4—4 in Fig. 2 of one side of the machine, and Fig. 5 a detail view illustrating the money column more 35 clearly.

In said drawings the portions marked A represent the frame of the machine, B money containing columns, and C a reciprocating carrier on which the push-bars and 40 operating mechanism are mounted. The frame A is preferably of metal and consists

of appropriate side pieces supported on legs a and having a top A¹ which is formed double, or hollow, for a purpose to be presently described, and with its forward end 50 formed with pockets to receive the money columns B.

The money columns B are of the form best shown in detail in Fig. 5, being of metal, with one end open and also with a vertical slot in one side, and are adapted to contain a number of coins of any denomination that may be desired. In Fig. 5 the column is shown in operative position and filled with coins, and alongside said column is 60 illustrated a coin retaining device consisting of a bar 10 with a disk 11 at each end adapted to slip over the ends of the money column B, said bar having a handle 12 adapted to project through the slot in the 65 money column receiving pocket, by which said coin retaining device may be removed from the coin holder after it has been put in position in the machine. Said coin holders are each provided with a follower 13 70 adapted to rest upon the top of the column of coins and having a finger 14 projecting through the slot in the holder and in the pocket in the frame, for a purpose to be presently described. 75

The reciprocating carrier C is a plate of appropriate size and construction mounted in ways in the side pieces of the frame A and provided with a rack-bar 15 on its under side which engages with a pinion 16 80 mounted on a crank-shaft 17, which is journaled in suitable bearings depending from said side pieces of said frame. Said crank-shaft is provided with a handle 18 by which it is operated. A pivot shaft 19 is mounted 85 in bearings 20 on the top of the carrier C and extends entirely across said carrier from side to side. A series of push bars 21, 22, 23, 24, 25, 26, 27, 28, 29, 30, 31, and 32 are mounted to rock on said pivot shaft, 90 the forward ends extending to points adjacent to the money columns when in normal

position, and their rear ends extending backward a sufficient distance to be covered by the operating levers.

A series of rectangular operating levers 5 33, 34, 35, 36, 37, 38, 39, 40, 41, 42, 43, and 44 are mounted on said pivot shaft 19 above the upper surfaces of said push bars. Each of said levers is in the form of a four-sided rectangular frame, and they are of varying 10 sizes so that they can be "nested" or arranged one within the other in a series, as shown most clearly in Fig. 2. Each of said bars has a depending ear at each end, formed with a perforation through which the 15 pivot shaft 19 extends. Each one of the push bars is formed with recesses in its upper side, adapted to receive the lower edges of the rocking rectangular levers, except one, an upwardly extending lug 45 being formed 20 between the recesses under one of said levers on each side of the pivot shaft 19, which lugs serve to establish an operative bearing between said push rod and said lever. This construction will be best understood by an 25 examination of Fig. 3, wherein push rod 27 is shown in elevation and the lever 38 is shown with its lower edge resting on the upper surface of the lugs 45 formed between the recesses in the upper edge of said push 30 rod, which recesses are adapted to receive the lower edge of all the other levers when tilted in either direction and render said push rod inoperative by the tilting of said other levers. This arrangement continues 35 throughout the mechanism, one of the levers being arranged in a similar manner to operate, when tilted, one of the push rods to throw its outer end up or down, as the case may be.

40 A series of selecting keys 46 are mounted on the lower ends of spring-mounted push rods 47 behind the pivot shaft 19, and another series of keys 48 are mounted on spring-mounted push rods 49 in front of 45 said pivot shaft 19. Said push rods are of a common form, each having a head, or button, on its upper end on which is inscribed the denomination of the coin, or the sum of money which is intended to control in connection with the operation of the 50 machine. A coiled spring 50 is interposed between a collar 51 on each of said push rods and the lower part of the hollow top of the casing, and operate to normally hold 55 said keys in elevated position. In the arrangement of the keys 46 and 48, the faces, which contact with the top edges of the levers beneath, are so formed by notching or recessing that those levers operated by forcing down one key will operate to tilt into

operative relation with the money columns those push rods necessary to aggregate the sum indicated on the top of its push button. By referring to Fig. 3, it will be noticed that key 46 is formed on its lower edge to 65 contact with the top edge of levers 33, 34, 35, 36, and 38. These several levers will tilt push rods 27, 29, 30, 31, and 32, throwing the forward ends of said levers upward into position so that the ejecting head 52 on the 70 top of said push rods at their forward ends will be in position to pass through the slot in spring plate 53 beneath the several money columns indicated and eject a coin from each of said money columns, which 75 will slide out over the curved outer edge of said support 53 and fall into a trough 54 with an inclined bottom and slide to the end thereof where it can be received by the user. The coins so discharged will aggregate the amount indicated on the button pushed. By forcing down key 48 on the opposite side of pivot shaft 19, these several keys will be reset, inasmuch as key 48 will 80 contact with the raised edge of the same 85 levers that have been moved into operative position by the corresponding key 46. A spring catch 55 is positioned adjacent to the end of each of the push rods and which cooperates with a projection 56 on said end 90 and serves to hold the push rod at the extreme limit of one of its rocking movements. Other spring catches 57, mounted alongside said push bars near their forward ends, contact with projections on the side of said bars 95 for the same purpose. It will be understood, of course, that one set of said springs may be dispensed with if desired, and also that any other form of retaining device preferred and found appropriate may be substituted.

In the use of this machine it will be understood that the keys on the opposite sides of the rock-shaft 19 are intended to coöperate to produce the desired result. It will 105 also be noticed that the series of money columns consist of five columns for containing cents, four columns (5_a, 5_b, 5₁, and 5₂) for containing five-cent pieces, one column for containing ten-cent pieces, one column for containing twenty-five-cent pieces, and one column for containing fifty-cent pieces. It will be readily seen that with this combination of columns any sum from one cent to one dollar can be selected.

115 On the rear side of the rock-shaft the keys are numbered from 5 to 100 in successions of five-cent increases, which represent any sum of money likely to be tendered for the purchase, except the exact change. 120

On the opposite side, or on the forward side, of said rock-shaft are a series of keys 0, 1, 2, 3, 4, for selecting the cent columns, and then from 5 to 95 arranged in successive increases of five cents each; also a key E for restoring the mechanism in case of error. The key E has its bar portion 48 formed with a straight or unnotched edge extending across the several operating levers 33 to 44 on the rear side of the shaft 19, and is adapted, when depressed, to engage all of said levers and thereby restore the push bars 21 to 32 to normal position.

Let us suppose, for example, that the amount of a purchase is eighty cents, and that the purchaser tenders one dollar in payment. The operator first pushes down the key 100, which will set the push rods

necessary to aggregate said sum of one dollar. He then pushes down the push key 80, and also the key 0, which will throw down, and out of operative relation with the money columns, the keys necessary to aggregate the sum of eighty cents and also the cent keys. Then, by operating crank 18, the carriage C is run forward and the push rods remaining in operative position will throw out twenty cents in change, as one dime and two five-cent coins, which is the amount desired. Whenever an error occurs in setting the machine, by throwing down key E, all of the levers are restored to normal position when they can be re-set and the error corrected.

The money combinations involved in the operation of the machine are the following:

20   *Lower set keys raise trippers.*

100=Error=50—25—5₁—5₂—10—11111—5_a—5_b

50   Now, assuming that \$1.00 has been tendered for an eighty cent purchase, the one dollar key is depressed and operates to raise the push bars aggregating that amount plus five cents (viz. 100=50—25—5₁—5₂—10—11111—5_b). The key designating 80 cents of the upper bank is then pushed, and also the zero (0) key, which operate to depress the push bars of the denominations totaling 85 cents (viz. =80—0=50—25—5₁—11111.) These two operations then

produce the following combinations: (keys raised) 50—25—5₁—5₂—10—11111—5_b=(keys depressed) 50—25—5₁—11111.

In the bank of keys designated "Amount of money tendered" only that key designating the amount tendered is depressed, 115 i. e., from five cents and its multiples to one dollar, though in operation push bars totaling \$1.05 are raised. With the keys designated "Amount of purchase", the additional key, zero, together with the key in- 120

dicating the amount of the sale, must be pushed when the purchase is five cents or any multiple thereof up to ninety-five cents. Thus the five cents is discounted in the 5 transaction since the zero key designates five pennies, or the amount in excess. Where the amount of a purchase is less than five cents, or greater than five cents and not a multiple thereof (e. g. 3, 4, 18, 23, 32, or 97 cents), the "Amount tendered" keys are operated as before and the proper key or keys, to the amount purchased, of the

rear bank are pushed down, but not the zero key. The zero key is depressed only in transactions where pennies are not involved (e. g. 5, 10, 25, 45, 75, 90, and 95, etc.).

65

Suppose forty cents, in the denominations of four dimes, are tendered and the amount to be deducted is thirty-two cents, then the key #40 is pushed down in the front bank and keys #30 and #2 in the rear bank. 70 The combinations involved are then as follows:

70

Key #40 raises=5_a—11111—5_b

- 15 The push rods corresponding to 25 and 5₁ were not initially raised and therefore were not required to depress. The "equation" otherwise leaves a balance of eight cents or the correct amount of change to be delivered 20 by the machine. Do not press "0" key when there are odd cents. Thus 47=25—5₁—5₂—10, and 2.

In order to obtain the change from this 25 machine in coins of the larger denominations, I have devised a special money combination, by the use of which this result can be accomplished. Such a special money combination or system is necessary to secure the result stated, owing to the fact that our 30 money system is not a common multiple system. For instance, change aggregating eighty cents would, by the usual system, be delivered in nickels and dimes, but by the use of this machine, arranged and operated 35 in accordance with my system, such change would be delivered in fifty, twenty-five, and five cent coins. This system is, in fact, incorporated in the formation and arrangement of the keys and mechanism, whereby 40 the particular push rods necessary to secure the change in the denominations desired are brought into operative relation with the coin columns.

I have shown a means for automatically 45 indicating when the coin columns are exhausted, consisting of a rock-shaft 60, which is slightly offset or crank-shaped between its ends and adapted to contact with the lower end of a striker 61 which is adapted 50 to strike an alarm bell 62 mounted on a bracket 63 on the front end of the machine. A weighted striker 61 normally holds the offset or crank portion of the shaft 60 in horizontal position. When the weight 55 13 reaches the bottom of the money column, its arm 14 strikes said crank portion of the shaft 60 and turns the head of striker 61 back from the bell 62. As the arm 14 passes said crank, the weight of the striker will 60 cause it to fall forward and hit bell 62, an-

nouncing to the operator that one of the 75 columns is empty, which can be readily ascertained by viewing the front of the machine and noting the position of the projecting arms 14. This column is then lifted out and another, filled with the coins of the 80 appropriate denomination, placed in the machine as before described, when it is then ready for further operation.

Having thus fully described my said invention, what I claim as new and desire to 85 secure by Letters Patent, is:

1. In a money changing machine, the combination, of a frame, a series of coin containing receptacles mounted on the frame, a carriage mounted on the frame, a plurality 90 of coin ejecting rods fulcrumed on the carriage, banks of keys located respectively on either side of the fulcrums of said rods and operable to set and reject said coin ejection rods, and means for operating the carriage 95 to eject the coins by the rods set, substantially as set forth.

2. In a money changing machine, the combination, of a frame, a series of coin containing receptacles mounted on the frame, a carriage mounted on the frame, a plurality of coin ejecting rods fulcrumed on the carriage, a plurality of levers fulcrumed on the carriage and operable to engage said coin ejecting rods, banks of keys located respectively on either side of the fulcrums of said levers and operable to engage the levers to set and reject said coin ejecting rods, and means for operating the carriage to eject the coins by the rods set, substantially as set 110 forth.

3. In a money changing machine, the combination, of a frame, a series of coin containing receptacles mounted on the frame, a carriage mounted on the frame, a plurality 115 of coin ejecting rods fulcrumed on the carriage, a plurality of levers fulcrumed on the carriage and adapted to engage with said ejecting rods on either side of the fulcrums thereof, a bank of keys located on one side 120

of said lever fulcrums selective to set said coin ejecting rods by said levers, a bank of keys on the opposite side of said lever fulcrums selective to reject the set coin ejecting rods by said levers, and means for operating the carriage to eject the coins by the rods set, substantially as set forth.

4. In a money changing machine, the combination, of a frame, a series of coin containing receptacles mounted on the frame, a plurality of fulcrumed coin ejecting rods, a plurality of fulcrumed levers comprising nested rectangular frames adapted to engage with said ejecting rods on either side of their respective fulcrums, keys selective to engage said levers to set and reject said coin ejecting rods, and means to operate the rods set to eject the coins, substantially as set forth.

5. In a money changing machine, the combination, of a frame, a series of coin containing receptacles mounted on the frame, a carriage mounted on the frame, a plurality of coin ejecting rods fulcrumed on the carriage, a plurality of levers comprising nested rectangular frames fulcrumed on the carriage and adapted to engage with said ejecting rods on either side of the fulcrums thereof, keys selective to engage said levers to actuate said ejecting rods, and means to operate the set rods to eject the coins, substantially as set forth.

6. In a money changing machine, the combination, of a frame, a series of coin containing receptacles mounted on the frame, a plurality of coin ejecting rods fulcrumed in the frame, a plurality of levers comprising nested rectangular frames fulcrumed in the frame and adapted to engage said ejecting rods on either side of the fulcrums thereof, a bank of keys operable to engage said levers to selectively reject the ejecting rods set, a single key for simultaneously rejecting all ejecting rods set, and means for actuating the set rods to eject the coins, substantially as set forth.

7. In a money changing machine, the combination, of a frame, a series of coin containing receptacles mounted on the frame, a carriage mounted to reciprocate on the frame, a plurality of coin ejecting rods fulcrumed on the carriage, a plurality of levers fulcrumed on the carriage and operable to engage said coin ejecting rods on either side of the fulcrums thereof, keys operable to engage said levers to set said ejecting rods, detents for holding the levers in set position, keys for engaging the levers to reject the ejecting rods set, and means for actuating the set rods to eject the coins, substantially as set forth.

8. In an automatic change making machine, the combination of a frame, push rods pivotally mounted on a common center and to reciprocate therein, coin delivering receptacles arranged out of the normal path of said push rods, a series of rectangular levers pivoted to extend above and contact with said push rods on both sides of said center, trippers arranged to throw said levers and rock said push bars to register with said receptacles, means for reciprocating said push rods, and means for returning said push rods to normal position, substantially as set forth.

9. In an automatic change making machine, the combination of a frame, push rods pivotally mounted on a common center and to reciprocate therein, coin delivering receptacles arranged out of the normal path of said push rods, a series of rectangular levers pivoted to extend above and contact with said push rods on both sides of said center, trippers arranged to contact with said levers on both sides of said center, a key for operating the trippers on one side of said center to rock said push rods on their pivots to register with said receptacles, and a key for operating the trippers on the opposite side of said center for returning the push rods to the normal position, substantially as set forth.

10. In an automatic change making machine, the combination of a frame, push rods pivotally mounted on a common center to reciprocate therein, coin delivering receptacles arranged out of the normal path of said push rods, a series of rectangular levers pivoted to extend above and contact with said push rods on both sides of said center, trippers arranged to contact with said levers on both sides of said center, a series of keys for operating said trippers to rock one or more of said push rods on their pivots to register with corresponding receptacles, a second series of keys adapted to operate the trippers on the opposite side of said center for returning said push rods to normal position, means for reciprocating said push rods, and means for returning the remaining deflected push rods to normal position after they have been reciprocated, substantially as set forth.

11. In a money changing machine the combination of receptacles for holding coins in piles of their respective denominations, means for ejecting the coins from said receptacles, levers disposed in operative relation to said coin ejecting means, and banks of keys constructed and arranged to coöperate with said levers, those in one bank for

selecting and those in the other bank for rejecting the coin ejecting means in accordance with the following money combinations:

<i>Selecting bank.</i>	<i>Rejecting bank.</i>
